UNITED STATES PATENT OFFICE

113,591

DESIGN FOR LACE

Edward E. Bancroft, West Warwick, R. I.

Application December 3, 1938, Serial No. 81,553

Term of patent 3½ years

To all whom it may concern:

Be it known that I, Edward E. Bancroft, a citizen of the United States of America, residing in West Warwick, county of Kent, and State of Rhode Island, have invented a new, original, and ornamental Design for Lace, of which the following is a specification, reference being had to the accompanying drawing, forming part thereof, wherein the figure is a plan view of a piece of lace showing my new design. The dot and dash lines on the drawing outline substantially a design unit, which unit is repeated in regular succession as indicated by the extensions beyond the unit boundaries.

The design is characterized by a pair of grouped solid and stem leaf units arranged alternately upon a net background, said leaf and stem units being outlined and ribbed by a superimposed thread which continues connectively from leaf to leaf upon the net background of the lace as shown.

I claim:

The ornamental design for lace, substantially as shown and described.

EDWARD E. BANCROFT.
